UNITED STATES PATENT OFFICE.

JOHN F. MACDOUGALD, OF ATLANTA, GEORGIA.

TAMPER.

Application filed June 15, 1927. Serial No. 199,067.

This invention relates to tamping devices and more particularly to a pan-like tamper having lugs projecting from the bottom portion of the tamper to force the stone or other aggregate in concrete below the surface. This results in a smooth surface on the concrete. These lugs may be either solid or tubular and if the latter embodiment is employed will result in a device which allows both air and water to flow to the surface of the concrete which is being laid.

In the drawings wherein I have shown the preferred embodiment of my invention,

Figure 1 is a plan view of the tamper,
15 Figure 2 is a vertical section taken on line
2—2 of Figure 1,

Figure 3 is a transverse vertical section, on
line 3—3 of Figure 1.

In the drawings, the numeral 1 designates
20 a pan-like body formed of sheet steel or other
desirable sheet material. This pan-like body
comprises a substantially flat bottom portion
2 and side portions 3. The side portions 3
are formed at an acute angle to the bottom
25 portion for a purpose to be described later.
It has been found that when the angle be-
tween the side portions 3 and the bottom 2
is approximately 45° the spreading action on
the concrete is very efficient. The bottom
30 portion 2 is reinforced by means of metal
strips 4 running longitudinally of the bottom
2 and extending to the corners of the bottom
adjacent the angles made by the sides 3.
The tamper is adapted to be vibrated by any
35 desired means, such for example as by a
pneumatic tool. Link 5 having a square boss
6 adjacent the top thereof and being bifur-
cated at its bottom portion, connects the
pneumatic tool (not shown) to the tamper.
40 As shown in Figures 2 and 3, there is a
swivel connection between link 5 and the bot-
tom portion of the tamper comprising an
ear 8, the base of which is riveted or other-
wise connected to the bottom portion of the
45 tamper, bolt 9, nut 10, and cotter pin 11. By
this means a swivel connection is provided
between the lever 5 attached to the pneumatic
tool, if such be employed, and the tamper
which allows the tamper to adjust itself to
50 the depressions or elevations which may be
formed in the concrete as freshly laid. The
swivel connection also provides for a slight
lost motion adapted to allow the tamper to
oscillate in a direction transverse to the nor-
55 mal direction of oscillation allowed by the
swivel connection.

Attached to the bottom 2 of the tamper are
a plurality of lugs 11 which may be either
solid or tubular. These lugs may be screwed
into holes in the bottom portion 2 of the
60 tamper or may be riveted in place as desired.

In Figures 1, 2 and 3 these lugs 11 are
shown tubular. It is preferred to form the
lugs tubular thus providing passages 12
which allow air and moisture to rise to the
65 surface of the concrete when the tamper is
operated.

In the operation of my invention the tam-
per is vibrated by any desired means and the
lugs projecting below the bottom of the tam-
per force stones or other aggregate design-
70 nated 13 below the surface 14 of the concrete
which is being laid. The openings 12 in lugs
11 provide for releasing the air which may
have collected in bubbles and also the water
75 and allow it to flow to the top of the surface
as above indicated. When the tamper is
brought down in contact with the wet con-
crete the sides 3 of the pan-like body be-
cause of their angle with the bottom portion
80 exert a leveling and spreading action on the
concrete.

From the above it will be apparent that I
have provided a simple, durable and effi-
cient tamper which will force the gravel or
85 other concrete aggregate below the surface
and leave a smooth surface and in addition
because of the pan-like shape of the tamper
will exert a spreading action on the material
which has just been laid.

It is to be understood that the form of my
invention herewith shown and described is to
be taken as a preferred example of the same,
and that various changes in the shape, size,
and arrangement of parts may be resorted to
95 without departing from the spirit of the in-
vention or the scope of the subjoined claims.

I claim:

1. A tamping device comprising a pan-
like body portion, means for reciprocating
100 said body portion, and tubular lugs attached
to the bottom of said body portion and ex-
tending below said bottom portion the bores
of said lugs providing communication with
the interior of said body.

2. A tamping device comprising a pan-like
body portion, a link for reciprocating said
body portion, including a substantially flat
bottom and sides surrounding said bottom
and formed at an acute angle to and extend-
110 ing above said bottom, swivel connections be-
tween said link and said body portion, and

tubular lugs attached to the bottom of said body portion and extending below said body portion, the bores of said lugs providing communication with the interior of said body.

5. A tamping device comprising a pan-like body portion, a link for reciprocating said body portion, swivel connections between

said link and said body portion, and tubular lugs attached to the bottom of said body portion and extending below said body portion, the bores of said lugs providing communication with the interior of said body. ¹⁰

In testimony whereof I affix my signature.
JOHN F. MACDOUGALD.
